United States Patent Office.

S. P. LOOMIS, OF PHILADELPHIA, PENNSYLVANIA.

Letters Patent No. 98,605, dated January 4, 1870.

IMPROVED WINDOW-JACK.

The Schedule referred to in these Letters Patent and making part of the same.

To all whom it may concern:

Be it known that I, S. P. LOOMIS, of the city and county of Philadelphia, in the State of Pennsylvania, have invented a new and improved Window-Jack; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved window-jack.

Figure 2 is an inverted plan view of the same.

Similar letters of reference indicate corresponding parts.

This invention relates to certain improvements on the window-jack, for which Letters Patent, No. 71,027, were granted to me on the 19th day of November, 1867.

The invention has for its object to simplify the construction of the window-jack, and to allow the same to be readily folded together.

The invention consists in the general arrangement of parts, and more particularly in the application of a reversible, and in various ways adjustable slide or inner bracket.

A, in the drawing, represents the platform of my improved window-jack. This platform is preferably made of one single board of suitable size, but may, if desired, be composed of two or more pieces.

To the outer part of this platform are, on the under side, secured ribs a a, which hold the pivot-pins b for the outer bracket B.

This outer bracket is composed of two or more legs c c, which are pivoted to the ribs a, and which are or may be connected with each other by a cross-bar, d.

A chain or rope, e, connects the lower part of the bracket B with the platform, to retain the bracket in the proper positions.

The upper ends of the legs c are made to fit into mortises formed in the under side of the platform, when the device is applied. The bevelled lower ends of the said legs are then in a vertical position to fit against the outer wall, as shown by black lines in fig. 1.

O represents the inner bracket or slide. It is a suitable slotted frame, fitted upon the inner part of the platform, so that it can slide on the same.

It can be locked to the platform in any position, by

means of one or more pins f f, fitted through apertures of the platform, as shown.

The device is applied by placing the platform through a window, and by drawing it in until the ends of the legs c fit against the outer wall. The slide C is then adjusted within the room, until it fits against the wall on the inside, and is then locked. The platform is thus securely arranged to support a person on its outer part.

In case there are benches or other devices in the way of the slide C, the same may be reversed, as by red lines in fig. 1, to project upward from the platform.

The device is easily folded together by swinging the frame B against the under side of the platform, and by fitting the frame C in a horizontal direction upon the platform, as in fig. 1.

To enable this arrangement, the frame C has a slot, g, which, in the ordinary position, is above the platform, but which may be used to fit the frame upon the platform, as in fig. 2, in which position C will rest flush on the under side of A.

A cross-bar, h, on the frame C, fitting over the ends of the legs c, will keep the frame B in the folded-up position.

The pins f may also be used to lock the frame C, when thus fitted upon the platform.

The apparatus is very convenient, as it can be readily applied to all windows, and as it is readily packed together and conveyed.

Having thus described my invention,

What I claim as new, and desire to secure by Letters Patent, is—

1. The slide or bracket C, when provided with double slots to allow its being adjusted on the platform A in a vertical or horizontal position, and, when reversible, substantially as herein shown and described.

2. The window-jack, consisting of the platform A, pivoted outer bracket B, and inner reversible slide C, all arranged and operating substantially as herein shown and described.

The above specification of my invention signed by me, this 17th day of May, 1869.

S. P. LOOMIS.
